UNITED STATES PATENT OFFICE.

EDWIN C. WASHBURN, OF MINNEAPOLIS, MINNESOTA.

CAR-COUPING.

SPECIFICATION forming part of Letters Patent No. 593,951, dated November 16, 1897.

Application filed June 24, 1897. Serial No. 642,068. (No model.)

To all whom it may concern:

Be it known that I, EDWIN C. WASHBURN, a citizen of the United States, residing at Minneapolis, in the county of Hennepin and State 5 of Minnesota, have invented certain new and useful Improvements in Car-Couplers; and I do hereby declare the following to be a full, clear, and exact description of the invention, such as will enable others skilled in the art to 10 to which it appertains to make and use the same.

My invention relates to car-couplers, and has for its object to generally improve the construction and operation of the same.

To the ends above noted my invention consists of the novel devices and combinations of 15 devices hereinafter described, and defined in the claims.

My invention is illustrated in the accompanying drawings, wherein, like letters referring to like parts throughout the several 20 views—

Figure 1 is a perspective view, with some parts in section, showing the head of my improved coupler with the locking dog or pin in 25 its normal or locked position. Fig. 2 is a transverse vertical section taken through a portion of the coupler substantially on the line X² X² of Fig. 1 and illustrating also the normal or locking position of the locking dog 30 or pin and of the so-called "retaining device." Fig. 3 is a perspective view, with some parts shown in section, illustrating the coupler with its locking dog or pin partially raised. Fig. 4 is likewise a perspective view with some 35 parts shown in section, but illustrating the coupler with the knuckle thereof open and the locking dog or pin sustained by the tail thereof. Fig. 5 is a transverse vertical section taken substantially on the line X⁵ X⁵ of 40 Fig. 4. Fig. 6 is a perspective view of the coupler, showing the knuckle closed and the lock dog or pin set in a position in which it will permit the knuckle to be freely opened. Fig. 7 is a transverse vertical section taken 45 approximately on the line X⁷ X⁷ of Fig. 6; and Figs. 8 and 9 are respectively views in perspective and side elevation showing a portion of the coupler, a portion of one of the transverse end timbers of the car, and different 50 modifications of the lock dog or pin lifting device.

a indicates the draft-timbers, and a' one of the transverse end timbers or beams, of a car.

b indicates the body or draft-bar section of the coupler, which, as shown, is cast integral 55 with a recessed coupler-head b', which is provided with the ordinary heavy hinge-lugs b².

c indicates the knuckle or jaw, which is pivotally connected to the lugs b² of the coupler-head b' by means of a pintle or pivot-bolt d. 60 The inner or tail end of the knuckle is constructed with a segmental dog or pin sustaining surface c' and with a raised shoulder or ledge c², which are adapted for co-operation with the lower end of the locking dog or pin 65 in a manner which will also be more clearly brought out later on.

f indicates the locking dog or pin, which is mounted to work through a suitable seat b⁴, formed in the top of the coupler-head. At 70 one of its lower corners the dog or pin f is provided with a depending guide-lug or extension f', which is adapted to work through a suitable seat b⁵, formed in the bottom of the coupler-head b. The coupler-head b is 75 also provided with a cam-lug b⁶, which is located rearward and just out of the path of the tail end of the knuckle c, with one wall thereof forming an upwardly-extended guide-surface of one side of the guide-lug seat b⁵. 80 Both the top of this cam-lug b⁶ and the bottom of the guide-lug f' are beveled, so that their engagement will cam the dog or pin f into such position that said guide-lug f' will fall into the seat b⁵. The pin-seat b⁴ is laterally expanded, so that when said dog or pin 85 is raised far enough to permit the guide-lug f' to clear the cam-lug b⁶ said dog or pin is free to swing sidewise and its lower end to be engaged with the ledge or shoulder c², as illustrated in Fig. 6. In this position the dog or pin is sustained in its unlocking position by the shoulder or ledge c², and the knuckle c is 90 free and may be opened whenever sufficient force is applied thereto to turn the same on 95 its pivot.

The pin-lifting device is so applied to the same that the act of raising the pin or dog will also cause the dog to swing sidewise and engage the shoulder or ledge c². This dog-lifting device is also arranged to operate or release a retaining device which normally 100

locks and holds the locking dog or pin in its lowermost or locking position. This construction is preferably substantially as follows: 5 *g* indicates a retaining-hook which is pivotally connected to the head of the lock dog or pin at a point offset from its center of gravity on that side of said dog toward which it is adapted to swing for engagement with the shoulder or ledge *c*² on the tail of the knuckle. 10 The free end of this retaining-hook *g* is normally held by its own gravity in engagement with a detent or notch *b*⁷, formed in that portion of the coupler-head which surrounds the seat *b*⁴. When thus engaged, the retaining- 15 hook *g* securely locks and holds the dog or pin in its lowermost or locking position, so that the same cannot be released or moved by force applied directly to the said locking dog or pin. This makes it impossible for the 20 locking dog or pin to be worked out of its seat or accidentally unlocked. The lower end of the lifting connection *k* is attached to the retaining-hook *g* at a point offset from its point of attachment to the locking-dog in a 25 direction toward its free end, so that when the lifting strain is applied through the connection *k* said retaining-hook *g* will first be disengaged from the notch or detent *b*⁷ and then the said lifting strain will become effective to raise said locking-dog into its unlocking 30 position.

Assuming that the locking-dog has been set, as indicated in Fig. 6, the action under the opening movement of the knuckle will be 35 as follows: The forward upper corner of the pin-sustaining surface or flange *c*' on the tail of the knuckle will strike the guide-lug extension *f*' of the dog or pin *f* and will positively force or carry the same into vertical 40 line with the seat *b*⁵. At this point the flange or surface *c*' will be carried out of engagement with the guide-lug *f*' in virtue of the fact that the said lug *f*' in its lateral movement moves tangentially to the movement of 45 said surface *c*', and the ledge or shoulder *c*² will be carried beyond or from under the bottom of the pin *f*, thus permitting said pin or dog *f* to fall onto the surface or flange *c*'. The surface or flange *c*' will sustain the pin 50 in the position illustrated in Fig. 3 until the knuckle is again closed. In this position (illustrated in Fig. 3) it will be noted the guide-lug *f*' of the pin or dog *f* has fallen below the cam-faced or beveled top of the cam-lug 55 *b*⁶, and hence will prevent the locking dog or pin *f* from being moved laterally under the return movement of the knuckle by the frictional engagement between the bottom of said dog or pin and the surface or flange *c*'. When 60 the tail of the knuckle reaches its normal or innermost position, it will be moved inward of the bottom of said dog *f* and the dog will be free to fall by gravity into its normal or locking position. (Indicated in Fig. 1.) When 65 the locking dog or pin is released from the sustaining surface or flange *c*', as just described, the dog-retaining hook *g* will, under

the action of the gravity of the parts, cam itself into engagement with the notch or detent *b*⁷.

70 The locking dog or pin *f* is of that class of pins or dogs which are usually designated as "vertically-movable" locking pins or dogs. For a specific purpose I mount this pin or dog for movement on a line deviating somewhat from the vertical and inclining rearward, or toward the body of the car. By means of a connection, hereinafter described, between the locking pin or dog and the body of the car said pin or dog may, in virtue of its inclined position, be much more easily drawn or released in case the coupler is torn loose from the car than if set for movement in a true vertical position. In the construction shown the locking pin or dog *f* is provided on its rear face 75 with a vertically-elongated notch *f*², and the coupler-head is provided with a removable transverse pin *f*³.

80 Directing attention now to the pin-lifting device, *k*' indicates a rock-shaft mounted in keepers *k*² *k*³ on the transverse beam *a*' with freedom for rotary as well as a limited endwise movement. At one side of the car the rock-shaft *k*' is bent off at a right angle to form an operating-lever or handpiece *k*⁴, and at its other end it is provided with a projecting arm *k*⁵. The keeper *k*³ is provided with a notch *k*⁶, into which the arm or handpiece *k*⁴ is adapted to be moved by endwise movement of the shaft *k*' to hold said arm *k*⁵ in its 85 uppermost position. The free end of the arm *k*⁵ is flattened and perforated, as shown at *k*⁷. In the construction illustrated in Fig. 8 a rod or connection *k*⁸ with upper-end head *k*⁹ works 90 loosely through the perforated end *k*⁷ of the arm *k*⁵ and has its lower end pivoted to a lug *f*⁴ on the upper end of the locking-dog *f*. In the construction illustrated in Fig. 9 the lower end of the rod or link *k*⁸ works through one 95 end of a buckle or spring-containing frame *k*¹⁰ and is pinned or otherwise secured to a head *k*¹¹, which is mounted to reciprocate in suitable guides *k*¹², formed in said buckle *k*¹⁰. The lower end of the buckle *k*¹⁰ is shown as 100 provided with a lug or ear *k*¹³, which is secured between the ears *f*⁵ on the upper end of the locking-dog *f*. *k*¹⁴ indicates a spring 105 which is coiled on the rod or link *k*⁸ and is compressed between the sliding head *k*¹¹ and the upper end of said buckle *k*¹⁰. The guides 110 *k*¹² in the buckle *k*¹⁰ permit a limited movement of the sliding head *k*¹¹ and then act as stops to render the connection rigid against further extension. Furthermore, said guides 115 *k*¹² are only so extended that they will not permit the spring *k*¹⁴ to reach the limit of its compression.

120 With the ordinary chain connection between the arm of the lifting device and the locking-dog the links of the chain are very liable to become twisted one upon the other or snarled, so to speak, so that the length of the connection becomes shortened for the time being. This will often prevent the locking 125

dog or pin from falling into its locking position, or it may prevent the lever or handpiece k^4 from being turned into engagement with the notch k^6 . However, with the form of coupling or link connections illustrated in Figs. 8 and 9 both the locking dog or pin and the lever-operated devices are always free to move to their limits, as the rod or link is always free to slip through the perforation of the lift-ing-arm k^5 . The flexible connection is adapt-ed to yield, so as to adapt itself to the different positions required, as the coupler moves forward and backward. It is of course evi-dent that in both of the constructions illus-trated in Figs. 8 and 9 the lower end of the lifting connection, instead of being secured directly to the locking-dog, might be indi-rectly secured—as to the retaining-hook g , for example.

Attention is here called to the fact that the lower edge of the detent or notch k^6 of the keeper k^3 is beveled or inclined, as shown at 6¹⁵. In virtue of this incline the handpiece k^4 of the rock-shaft k' when forced against the same by endwise movement of said shaft k' will be engaged and frictionally held in whatever vertical position it happens to oc-
cupy when turned upward to raise the locking pin or dog into its unlocking or extreme uppermost position.

It will be understood, of course, that vari-ous alterations in the details of construction above described may be made without de-parting from the spirit of my invention. For instance, it will be understood that the re-taining device for holding the locking-dog in its locking position and certain other devices which coöperate therewith may be used in combination with a coupler employing a piv-oted or swinging locking-dog.

What I claim, and desire to secure by Letters Patent of the United States, is as follows:

1. The combination with a coupler, involv-ing a coupler-head, pivoted knuckle and lock-ing-dog, of a retaining device acting to secure said dog in its locking position, a sustaining surface or projection carried by the tail of said knuckle, adapted to move under said locking-dog and acting to hold said dog up-ward above a position in which said retain-ing device is operative to secure the same, and a releasing connection arranged to first release said retaining device and then move said dog into its unlocking position, substan-tially as described.

2. The combination with a coupler, involv-ing a coupler-head, pivoted knuckle and lock-ing-dog, of a retaining device acting to secure said dog in its locking position, a dog lifting or releasing device involving said retaining device as a section or link thereof, and a sur-face or projection carried by the tail of said knuckle and acting to hold said dog in a po-sition in which said retaining device is inop-erative to secure the same, when said knuckle is opened, substantially as described.

3. The combination with a coupler, involv-ing a coupler-head, pivoted knuckle or jaw and locking-dog, of a hand-operated dog-re-leasing device involving, a spring, and a 70 spring-holding bracket or buckle constructed to permit said spring to yield less than the limit of its elasticity and then to become rigid, to positively release the dog, substantially as described.

4. The combination with a coupler, involv-ing a coupler-head, pivoted knuckle and ver-tically-movable locking-dog, of a retaining device acting to secure said dog in its lock-ing or lowermost position, a surface or pro-jection carried by the tail of said knuckle and acting to hold said dog above the posi-tion in which said retaining device is active thereon to secure the same, while said knuckle is open, which retaining device is in the form 85 of a hook pivoted to said dog and forming part of the releasing or dog-lifting connec-tion, substantially as described.

5. In a coupler of the character described, the combination with the pivoted knuckle, of 90 a locking dog or pin mounted in the coupler-head, with freedom for vertical and a limited lateral movement, a surface or flange carried by the tail of said knuckle and acting to pre-vent said locking dog or pin from falling into 95 a locking position while the knuckle is open, and a raised shoulder or ledge on the tail of said knuckle, upon which the lower end of said dog or pin is adapted to be engaged to set said dog so that the knuckle may be 100 opened, substantially as described.

6. In a coupler of the character described, the combination with the pivoted knuckle, of 105 a locking dog or pin mounted in the coupler-head, with freedom for vertical and a limited lateral movement, a surface or flange carried by the tail of the knuckle and acting to pre-vent said locking dog or pin from falling into 110 its locking position while the knuckle is open, a raised shoulder or ledge on the tail of said knuckle upon which the lower end of said dog or pin is adapted to be engaged to set said dog so that the knuckle may be opened, and coöperating stop projections or surfaces, one on said locking-dog and the other on the 115 coupler-head, which projections or surfaces prevent the lateral movement of said dog or pin when resting upon the lower surface or flange of said knuckle, but permit the lateral movement of the said dog when raised for 120 engagement with the said raised shoulder or ledge of said knuckle, substantially as de-scribed.

7. In a coupler of the character described, the combination with the recessed coupler-head $b' b^2$, of the pivoted knuckle c , the tail of which is formed with the lower and ex-tended dog-sustaining surface or flange c' and the raised shoulder or ledge c^2 , the vertically-movable locking dog or pin f coöperating 130 with the tail $c' c^2$ of said knuckle and pro-vided with the guide-lug projection f' , and

the cam-lug b^6 formed on the coupler-head and coöperating with said guide-lug j' , all substantially as described.

8. The combination with a coupler having 5 a vertically-movable locking dog or pin, of a dog-lifting device, involving the rock-shaft k' provided with the arm k^5 with perforated head k^7 , and the link or rod k^8 working loosely through said perforated head k^7 , provided, at 10 its upper end with the head or stop k^9 and pivotally secured, at its lower end, to the head of said pin or dog, substantially as described.

9. The combination with a coupler, involv-

ing a coupler-head, a pivoted knuckle or jaw 15 and a locking-dog, of a hand-operated dog-releasing device, involving the rod k^8 with head k^{11} , the buckle k^{10} in which said rod k^8 and head k^{11} work, and the spring k^{14} compressed between one end of said buckle k^{10} 20 and said head k^{11} , substantially as described.

In testimony whereof I affix my signature in presence of two witnesses.

EDWIN C. WASHBURN.
